UNITED STATES PATENT OFFICE.

HENRY B. LEVY, OF NEW YORK, N. Y.

DESIGN FOR A DRESS-SHIELD FASTENER.

SPECIFICATION forming part of Design No. 34,164, dated March 5, 1901.

Application filed February 9, 1901. Serial No. 46,753. Term of patent 7 years.

To all whom it may concern:

Be it known that I, HENRY B. LEVY, a citizen of the United States, residing in the city of New York, borough of Manhattan, county and State of New York, have invented and produced a new and original Design for a Dress-Shield Fastener, of which the following is a specification, reference being had to the accompanying drawings, forming part hereof, **10** wherein—

Figure 1 is a perspective view of my newly designed dress-shield fastener, the tongue or prong on the reverse side being shown in dotted lines. Fig. 2 is a face view of said **15** reverse side, Fig. 3 a side elevation, of the fastener.

My design relates to that class of fasteners or pins which are adapted to attach dress-shields and the like to garments or for analogous uses. **20**

The leading feature of the design consists in a plate having a tongue or prong on one side thereof rising from and extending length-

wise of the plate, two openings in said plate, and two prongs rising from and extending **25** lengthwise of the plate on the side opposite the first-mentioned tongue or prong and in line with the openings in the plate, the last-mentioned prongs being bent at an angle in line with their respective openings. **30**

In the drawings, A indicates the plate forming the body portion of the pin or fastener. A' is the tongue or prong at the back, and B B are the two prongs located, respectively, in line with the openings a a in the plate A. **35** (See Fig. 1.) At a portion of their length the prongs B are bent inwardly, as at b, forming an angular point (see Fig. 3) in line with the openings a.

What I claim is—

The design for a dress-shield fastener, substantially as herein shown and described.

40
HENRY B. LEVY.
